CIRCUIT CONTROLLING MECHANISM

Filed Dec. 14, 1925

Inventors:—

John T. Miller and Michael Hanley
Brown Bottener. Danner Att'y's.

UNITED STATES PATENT OFFICE.

JOHN T. MILLER AND MICHAEL HANLEY, OF CHICAGO, ILLINOIS.

CIRCUIT-CONTROLLING MECHANISM.

Application filed December 14, 1925. Serial No. 75,206.

Our invention relates, in general, to electrical signalling systems and more particularly to electric controlling mechanisms therefor. Specifically, the present invention 5 contemplates the provision of an improved circuit controller particularly adapted for use in conjunction with fire alarm signalling systems and police signalling systems.

In such systems, call or signal boxes are 10 usually employed for initially setting the signalling mechanism into operation. These call boxes are manually controlled and are in general operable by opening the same and grasping some form of trip member to 15 set the signal sending apparatus therein into operation.

We propose to provide automatic mechanism for controlling such call boxes as well 20 as for enabling them to be operated by a suitable switch or push button located at any distance therefrom.

The object of the present invention is to 25 provide improved electrical mechanism for operating a call box by a switch or push button at a distance therefrom.

In accordance with the general features of 30 the present invention there is provided circuit controlling mechanism of the character disclosed in our co-pending application, Serial No. 58,958, filed September 28, 1925, 35 for automatically rendering the push button circuit inoperative for a predetermined period of time once the button is depressed, for setting the box signal sender into operation and for operating an auxiliary signal 40 for a predetermined period of time. The circuit controlling mechanism is set in operation when the push button is initially depressed through the closing of the circuit by suitable solenoid mechanism.

Other objects and advantages of our invention will more fully appear from the following detailed description taken in connection with the accompanying drawing 45 which illustrates one embodiment thereof and in which the single figure is an elevation of a call box illustrating our novel electrical mechanism for automatically operating the same.

Referring now to the drawing in detail, 50 10 denotes a box or casing which may be made of any suitable metallic material and which may be of any usual construction. Since, in practice, such a box with the mechanism contained therein is referred to as 55 a call box, we shall refer to it as such in

the descriptive matter to follow. This call box may be of any well known type such, for example, as that employed in fire alarm signalling systems or in police signalling 60 systems.

While any form of signal sending apparatus and circuit may, of course, be employed and the same constitutes per se no part of our invention, we have illustrated 65 in a diagrammatic and convenient manner, for the sake of clearness, a possible form of such apparatus and have indicated the same generally by the reference numeral 15. This signal sending apparatus 15 is nothing 70 more or less than a clockwork including a main spring 12 mounted on a shaft 13 and attached at one end 13' thereto. The other end 12' of the spring 12 is attached to the framework 9. Associated with the shaft 13 75 is the usual gearing 11 as well as an escapement mechanism 15'. The framework also carries a shaft 14' operatively driven by the train of gears. Mounted on the shaft 14' 80 is a circuit breaking or code wheel 14 of a construction well known to those versed in the signal art.

The gearing 11 includes a train of gears 1, 2 and 3. The gear 1 is mounted loosely on shaft 13. The shaft has secured to it adjacent the gear 1 a ratchet wheel 4 which engages pawl 5. The pawl 5 is mounted at 6 on the gear 1 and is urged into engagement with the wheel 4 by a spring 7. The ratchet and pawl construction cooperate to 90 enable the shaft 13 to be turned in a counter-clockwise direction to wind up the spring 12 without turning gear 1. However, when the shaft 13 is turned in a clockwise direction by spring 12 the gear 1 will turn therewith to operate the signal sending apparatus 15. The gear 2 is splined to a shaft 8 suitably journaled in frame work 9. Also mounted on shaft 8 is a pinion 2' which meshes with and is driven by gear 1. The 100 gear 2 meshes with and drives a pinion 3' splined to shaft 14' upon which gear 3 is mounted. Thus it will be apparent that the shaft 13 is adapted to drive the code wheel 14 through the gears 1 and 2.

The escapement mechanism 15' comprises a detent 4' and a toothed wheel 5' both of which members may be of any conventional construction. The detent 4' is carried by an arm 6' connecting to framework 9. The wheel 5' is mounted upon a shaft 7' which is journaled in frame 9. Splined to shaft 7'

is a pinion 8' which meshes with and is driven by gear 3. The escapement 15' is adapted to control through the gears 1, 2 and 3 the return movement of shaft 13 under the effect of spring 12.

The teeth 16 on the circuit breaking wheel 14 are adapted to break the connection between leads 17 and 18 of a circuit 20 which is normally closed. Suitable contact spring fingers 17' and 18' may be associated with the leads 17 and 18 in any of the well known manners. The springs 17' and 18' are normally in contact but are adapted to be separated by a pivotally mounted arm 20 through the means of the code wheel 14. The circuit 20 constitutes the signal sending circuit and may include the usual instruments such as a sending key 21 and a receiver 22 including a solenoid 23 and a gong 24. The circuit 20 is normally closed as was previously mentioned and signals are transmitted thereover by intermittently breaking the circuit. The teeth 16 on the wheel 14 are arranged in such a manner as to be capable of breaking the circuit 20 a predetermined number of times to indicate the number of the call box 10. The instruments 21 and 22 may be of any well known construction and do not constitute per se any part of the present invention. They are illustrated, however, to show how they may be associated with our novel circuit controlling mechanism.

Attached to an end of the shaft 13 is a pull lever or arm 30 to one end of which is pivotally connected a link member 31 pivoted at its lower end to a plunger member 32. The lower end of the plunger member 32 is disposed within the center of a solenoid 33 and in reality constitutes a core therefor. Surrounding the solenoid 33 is a metallic frame 34 which serves as a support for the solenoid and as a means for securing it to the box 10. Also disposed in the bore of the coil or solenoid 33 is a stop member 35 for limiting the downward movement of the plunger 32. Upon the energization of the coil or solenoid 33, as will be more fully explained hereinafter, the plunger 32 is drawn downwardly into the coil of wire or solenoid pulling with it the lever arm 30 and winding up the spring 12 upon the shaft 13.

Mounted on and attached to the upper edge of the lever 30 is a tripping spring element 37 having one end projecting from the lever 30 forming a tripping spring 38. The other end of the tripping spring element 37 is formed into a lateral extension which constitutes a tripping spring 39. Attached to the lower edge of the lever 30 is a tripping spring element 40 having one end projecting therefrom in the same general direction as the spring 38 and constituting a spring 41 adapted to cooperate with the spring 38.

The other end of the tripping spring element 40 is formed into a projection constituting a tripping spring 42 adapted to cooperate with the tripping spring 39. The springs 38 and 41 are adapted to control a switch indicated generally by the reference numeral 45 and the springs 39 and 42 are adapted to control the operation of a switch indicated generally by the reference numeral 46. Both the switches 45 and 46 are of the snap type and are adapted to be set into either an open or closed position by the tripping springs associated therewith.

The switches 45 and 46 are substantially the same in construction and are both controlled through my novel circuit controlling mechanism. Since both the switches 45 and 46 are substantially alike, it is thought that a description of one will suffice for both. Therefore, like reference numerals will be applied to similar parts in both of these switches. It should be noted that the switches are in different positions as well as in different planes so as to enable them to be accommodated by the limited amount of space afforded in the call box 10.

Each of the switches includes a slate base 50 which is fastened to the box or casing 10. Attached to the face of the base 50 are a pair of spaced trunnions 51 and 52 each of which carries a set screw 53 and mounted on the other end of the base 50 are a pair of electric terminals 54 and 55. Fastened to the face of the base 50 intermediate the trunnions 51 and 52 and the terminals 54 and 55 are another pair of trunnions 56 and 57 equipped with set screws 58. Disposed intermediate the trunnions 56 and 57 is a cam member 59 pivotally carried by the set screws 58. The cam member 59 comprises a circular disk having two arcuate cut-out portions 60' and 61' the purpose of which portions will be described hereinafter. That is to say, the cam member 59 has a pair of pointed members 60 and 61 to fit into the ends of the set screws 58 permitting the cam to be moved angularly. The cam or trigger member 59 has integral therewith a projection 63 adapted to have a lost motion connection with the arm 30 of our device through the means of the springs 38 and 41. A switch member 64 extends under the cam or trigger member 59 intermediate the trunnions 56 and 57. This member has formed on one end a pair of pointed studs 65 and 66 which are pivotally disposed in the set screws 53, thus forming a pivotal mounting for one end of the member 64. This member 64 may be made of brass or any other suitable material. The other end of the member 64 carries a contact piece 68 adapted to bridge the terminals 54 and 55. The member 64 has formed thereon intermediate its ends an arcuate shaped projection 69 adapted to be engaged by the periphery of 130

the cam or trigger member 59. When the projection 69 is engaged by the cut-out portion 60' as shown in the drawing the switch member 64 will be in its open position. On the other hand when the projection 69 is contacted by the portion 61' of cam member 59 the switch member 64 will be in its closed position. The member 64 is at all times urged upwardly about its pivot by a band 10 spring 70 disposed intermediate it and the base 50.

Normally, the spring 70 will force the member 64 upwardly causing the contact piece 68 to be disconnected from the terminals 54 and 55. Upon movement of the previously mentioned lever arm 30, as will be more apparent as the present description progresses, the lost motion connection between it and the projection 63 operates the cam or trigger 59 depressing the member 64 and compressing the spring 70. This results in the terminals 54 and 55 being bridged and the associated circuit being closed.

Connected to the terminals 54 and 55, of the switch 46, are a pair of auxiliary signal circuit leads 71 and 72 of an auxiliary signal circuit 73. When the terminals 54 and 55 are bridged by the contact means 68 of the member 64, the signal will be operative.

The operation of the switch 46 is controlled by the springs 39 and 42. It should be noted that the spring 41 may be adjusted or rather moved further away or nearer to the lever arm 30 by means of a stud 74 attached to an end of the lever arm and a small nut 75 threaded thereon. That is to say, by turning the nut 75, the spring 42 may be moved to any desired position.

The springs 38 and 41 are adapted to alternately engage the projection 63 on the cam 59 of the switch 45 to either open or close the said switch. We have illustrated the spring 39 as being equipped with an auxiliary spring 76' integral therewith. The spring 76' is adapted to engage the projection 63. In order to adjust the position of the spring 76' with respect to the spring 38, we have provided a stud or screw 76 which ties the two springs 39 and 42 together. The position of the spring 76' through which the stud 76 passes may be varied by turning a nut 78 screwed onto the stud 76 intermediate its end.

Connected to the terminals 54 and 55 of the switch 46 are a pair of leads 80 and 81 of the circuit 82. Included in the circuit 82 is a battery 83, a push button 84 and a solenoid 85. The solenoid 85 has an armature 86 provided with a ball shaped end 87 for moving a contact spring 88 into engagement with a contact spring 89. It is apparent from the drawings that when the solenoid 85 is energized, the armature 86 will be drawn downwardly, causing the contact 88 to be moved into engagement with the

contact 89, closing the circuit 90 associated therewith. The circuit 90 includes the solenoid 33. The power line leads 91 and 92 of the circuit 90 may be connected to any suitable source of electrical power such, for example, as a 110 volt line. It is evident that when the contacts 88 and 89 are closed the circuit 90 will also be closed and the solenoid 33 therein will be energized.

The operation of our novel mechanism is as follows:

Upon depressing the button 84 which may be located in any position at a distance from the call box 10, the circuit 82 is closed. That is to say, for example, supposing some one in a bank or some other analogous place desires to operate a call box positioned on a street corner, he merely presses a push button such as the one designated by the reference numeral 84. Now, inasmuch as the contacts 54 and 55 of the switch 45 are normally bridged by the contact teeth 68, current from the battery will flow through the solenoid 85 energizing the same and pulling the armature 86 downwardly. The armature in turn moves the contact 88 into engagement with the contact 89 closing the circuit 90 and energizing the coil 33.

The coil 33 through the plunger 32 and the link 31 draws the lever arm 30 downwardly, storing up energy in the clock spring 12. It will be evident from the drawing that the escapement mechanism 15' will retard the return of the lever arm 30 to its initial position as previously mentioned. Also, in moving the pull lever 30 downwardly, the shaft 13 is caused to be turned, setting the clockwork associated therewith, as well as the signal sending apparatus, in a position ready to function. The lever 30 through the tripping spring 42 operates the cam 59 of the switch 46 to cause the member 64 to be urged outwardly away from the slate, panel or base 50 due to the urging effect of the spring 70. This results in the contact piece 68 being moved out of engagement with the contacts 54 and 55 opening the circuit 82 thereby rendering the button 84 ineffective to energize the coil 33.

Furthermore, the lever arm 30 through the trip spring 38 operates the cam 59 by coming into engagement with the projection 63 thereof. The cam 59 of the switch 45 through the cut-out portion 61' causes the member 64 to be moved inwardly towards the panel or base 50 bringing the bridge piece 68 into contact with the terminals 54 and 55 of the switch 46. This action causes the circuit 73 to be closed and sets into operation an auxiliary signal (not shown).

Now, upon the circuit 82 being broken, the armature 86 associated with the coil 85 immediately moves back to its former uppermost position due to the urging effect of a spring 100. The contact 88 thereupon moves

out of engagement with the contact spring 89 breaking the circuit 90 and thus de-energizing the coil.

The lever arm 30 is now free to move to its former position under the effect of the spring 12 in which energy has been stored. That is to say, a downward movement of the lever wound up the spring 12 and set the clockwork mechanism associated therewith in a condition for operation. The upward movement of the lever arm, however, is controlled by the escapement mechanism of the clockwork. The return movement of the lever arm 30 also sets into operation the circuit breaking wheel 14 which interrupts the normally closed usual fire or police alarm circuit 20 transmitting thereover the number of the call box. In the drawing, the wheel 14 is illustrated as being equipped with three spaced notches 16. Thus it will be seen that the number of this call box might be 1-2. Of course, it is to be understood that although we have illustrated the circuit 20 as being normally closed, it would work equally well, if instead of breaking the circuit, the wheel 14 could be arranged to close the circuit each time a notch thereof came into engagement with the contacts of the said circuit.

As soon as the lever arm 30 has moved a sufficient distance to bring the contact or trigger spring 41 into engagement with the projection 63 of the switch 45, the cam 59 thereof is operated resulting in the member 64 being moved away from the base 50 breaking the circuit 73 and rendering the signal associated therewith inoperative.

Also, upon the trigger spring 75 contacting the projection 63 of the switch 46, the cam 59 thereof reacts to force the member 64 towards the base 50 thereof bringing the contact or bridge piece 68 into engagement with the terminals 54 and 55 to connect the same and thus render the circuit 82 in a condition for operation once more. The upward movement of the lever arm 30 may be limited by any suitable means such, for example, as by a stop 101 attached to the framework 9 of the clock mechanism.

It is evident from the foregoing description that by depressing the push button 84 not only is the signal sending apparatus set into operation and the auxiliary signal operated, but the button circuit is broken making it impossible to energize the coils by further depressing the push button during the time that the clock mechanism is set to operate or in other words until the lever 30 has been restored to its normal position. This is a highly desirable feature, inasmuch as it frustrates the possibility of a person making it impossible for the lever arm 30 to be returned by continually depressing the push button.

Thus, it will be seen that we have pro-

vided a single plunger arrangement for contemporaneously operating a pair of switches and for operating suitable alarm signalling apparatus. Also, it will be seen that we have provided a very compact arrangement consisting of a minimum number of parts and having a very high degree of efficiency. Then too, our invention may be applied to the usual police and fire alarm call boxes with a minimum number of deviations from standard practice.

Moreover, through the adjusting mechanism previously described, it is possible to vary the time of effectiveness of both the tripping springs 42 and 75. Obviously, before these springs are brought into contact with the associated projections 63 of the snap switches 45 and 46, a predetermined period of time is caused to elapse. This period of time may be varied either by adjusting the escapement mechanism of the clockwork or by turning the nuts associated with the studs 74 and 76.

The tripping springs, in reality, constitute lost motion connections between the arm 30 and the projections 63 of the snap switches 45 and 46. A very slight pressure on the projection is necessary to operate the cam in either direction. The tripping springs exert just enough pressure upon the projection 63 to cause it to snap the switch in either direction.

The auxiliary circuit 73 may control the operation of any suitable signal whether it be of the visual or audible type for signalling that the push button 84 has been depressed. If, for example, the push button 84 be located in a bank, the auxiliary signal may be located in the quarters of the watchman or bank policeman.

Furthermore, by opening the call box 10 and pulling down on the lever 30, the mechanism associated therewith may be operated independently of the push button 84. Messages may be either transmitted or received by the policeman or fireman operating the call box by means of the two instruments 22 and 21. These instruments are well known to those skilled in the alarm box art.

We claim:

1. In combination, an electrical switch, a first means including a pull-lever for operating said switch, an adjustable lost motion connection between said lever and said switch, a second means for moving the said pull-lever in a given direction to actuate the switch, signal sending mechanism, a third means for slowly returning the pull-lever to its initial position and for operating the said signal sending mechanism, said latter means causing said first means to actuate said switch so as to return the switch to its initial position, and a fourth means controlled by the said switch for preventing said second means from being operated until the pull

lever is returned to its initial position after an operation thereof.

2. In combination, an electrical snap switch, means including a pull lever for operating the said switch, a lost motion connection between said switch and said pull lever, means including a solenoid for moving the said pull lever in a given direction to actuate the switch, signal sending mechanism, means for slowly returning the pull lever to its initial position and for operating the said signal sending mechanism including a spring and an escapement mechanism, said latter means causing said lever to actuate said switch so as to return the switch to its initial position and means controlled by the said switch for preventing said solenoid from being operated until the pull lever is returned to its initial position after an operation thereof.
- 20 3. In combination, an electrical switch including a plurality of terminals, a switch element for connecting said terminals and an extension associated with said element adapt-

ed to be actuated to open and close said switch, a pull lever, means for pulling the lever from one position to another, an element carried by said lever for moving said extension in one direction during the moving of said pull lever to cause said switch to be operated, signal sending mechanism, means including a spring and escapement mechanism for slowly returning the said pull lever to its initial position and for operating said signal sending mechanism, a second element associated with said lever adapted upon the return movement of said lever to actuate said extension of the switch after a predetermined period of time has elapsed to cause said switch to be operated and means controlled by said switch for controlling the operation of said pulling means.

In witness whereof, we hereunto subscribe our names this 10th day of December, 1925.

JOHN T. MILLER.
MICHAEL HANLEY.
